UNITED STATES PATENT OFFICE.

HENRY WISCHHUSEN, OF MELROSE, AND FRED WISCHHUSEN, OF MALDEN, MASSACHUSETTS.

DESIGN FOR A CHRISTMAS BELL.

53,952.

Specification for Design.

Patented Oct. 7, 1919.

Application filed May 23, 1919. Serial No. 299,354. Term of patent 14 years.

To all whom it may concern:

Be it known that we, HENRY WISCHHUSEN and FRED WISCHHUSEN, both citizens of the United States, and residents of Melrose and Malden, respectively, in the county of Middlesex and Commonwealth of Massachusetts, have invented a new, original, and ornamental Design for Christmas Bells, of which the following is a specification, reference being had to the accompanying drawing, forming part thereof.

Figure 1 is a side view of a Christmas bell, showing our new design.

Fig. 2 is a top view of the same.

We claim:

The ornamental design for a Christmas bell, as shown.

May 19, 1919.

HENRY WISCHHUSEN.
FRED WISCHHUSEN.
